UNITED STATES PATENT OFFICE.

EDWARD CUVELIER, OF HALIFAX, NOVA SCOTIA, CANADA.

SHOE-HEEL.

1,108,975.

Specification of Letters Patent.

Patented Sept. 1, 1914.

Application filed March 2, 1914. Serial No. 821,955.

To all whom it may concern:

Be it known that I, EDWARD CUVELIER, gentleman, of the city of Halifax, in the county of Halifax, Province of Nova Scotia, 5 Dominion of Canada, have invented certain new and useful Improvements in Shoe-Heels, of which the following is the specification.

This invention relates to shoe heels, and 10 the objects of the invention are to devise a new and particularly simple form of interchangeable heel for shoes and boots, which shall have the fewest possible working parts, and be very easily fitted and changed from 15 heel to heel.

The invention consists essentially in the novel construction and arrangement of parts hereinafter described, and illustrated in the drawing which forms part of this specification.

In the drawing, Figure 1 shows a shoe-heel of the usual construction, ready for the reception of my improved heel-piece or renewable heel. Fig. 2 shows in perspective 25 my improved heel, in the position adapted to be fitted to the heel shown in Fig. 1. Fig. 3 shows a sectional elevation of the heel-proper and the heel-piece when assembled. Fig. 4 shows a perspective outside arrangement of the parts when assembled.

Referring to the drawings, 10 represents the heel-proper, and 11 the heel-piece of rubber or the like, and which has the plate 12 secured to it. This plate 12 is used as the 35 means of securing the heel-piece to the heel proper, and also for keeping the heel-piece in proper alinement when on the heel-proper. The plate 12 is secured in the heel-piece by having the flanges 13 offset in the 40 Z fashion shown in Fig. 3, which I have claimed in prior application in the U. S. A., (date Feb. 5th, 1914, Serial No. 816683), and is also "dished" in the center as indicated by 14, the dished part being bent out 45 in the same direction as the flanges 13, namely into the rubber; this is done, to make the periphery of the heel bind against the periphery of the heel-proper, when the two are put together.

50 The plate 12 is provided with a number of offset projecting points 15, which are

formed integral with the plate preferably, and project on the opposite side from the flanges 13. These points or "stickers" are adapted to enter a short distance into the 55 leather of the heel-proper, and prevent a rotary motion of the heel-piece on its fastening screw 16, which is passed through an orifice 17 in the center of the depression of the plate 12 and screwed into the heel- 60 proper. The rubber of the heel-piece is formed with an opening 18 to admit of the head of this screw. In fitting these heels, the heel-piece is placed against the heel-proper in the position it is intended to occupy ultimately, and the fastening screw 16 is inserted and screwed home into the heel-proper; it may or may not be necessary to use an awl to start the hole 19 in the heel-proper for this screw. The "stickers" may 65 be caused to penetrate the heel-proper either by the pressure of the foot, and subsequent tightening of the screw, or by tightening of the screw only. When they have once penetrated the heel-proper they prevent rotation of the parts. If the heel-piece 70 becomes worn down at one corner, the heels of the right and the left shoe may be taken off, and changed for one another, and the "stickers" will at once center the shoe and 75 the heel-piece in their proper place. If new heels are fitted, they will automatically center themselves in the holes made by the "stickers" of the old heel-pieces.

Since many changes might be made in the 85 construction of this invention without departing from the spirit or scope of the annexed claims, it is intended that all matter contained in this specification be considered illustrative rather than as binding in detail. 90

What I claim as my invention is:—

1. In a shoe-heel, a heel-proper, a heel-piece, a dished metallic plate formed with offset Z flanges on one side and spurs on the other side secured thereto, said heel- 95 piece having a single transverse orifice approximately centrally situated, and a single wood-screw arranged to bind the parts together.

2. In a shoe-heel, a heel-proper, a heel-piece, a metallic plate formed of a single piece of sheet metal deformed to have Z

flanges on one side and spurs on the other side, said plate flanges being embedded in said heel-piece, and a single centrally situated binding member arranged to secure 5 said plate against said heel-proper and cause said spurs to engage said heel-proper.

In witness whereof I have hereunto set my hand in the presence of two witnesses.

EDWARD CUVELIER.
